UNITED STATES PATENT OFFICE.

EDWARD A. COOPER, OF BUFFALO, NEW YORK, ASSIGNOR OF ONE-FOURTH,
TO OGDEN P. LETCHWORTH, OF SAME PLACE.

HALTER-TRIMMING.

SPECIFICATION forming part of Letters Patent No. 284,541, dated September 4, 1883.

Application filed July 27, 1883. (No model.)

To all whom it may concern:

Be it known that I, EDWARD A. COOPER, of the city of Buffalo, in the county of Erie and State of New York, have invented a new and useful Improvement in Halter-Trimmings, of which the following is a specification.

The object of this invention is the construction of a light, simple, and neat halter-trimming or metallic fastening whereby the several straps of the halter are secured together; and my invention consists of the novel construction of the trimming, which will be hereinafter fully set forth, and pointed out in the claim.

15 In the accompanying drawings, Figure 1 is a perspective of a halter provided with my improvements. Fig. 2 is a vertical section, on an enlarged scale, of the lower end of a cheek-strap and the trimming whereby it is connected with the chin-strap. Fig. 3 is a side elevation of these parts. Fig. 4 is a side elevation of the trimming whereby the fixed end of the throat-latch is secured to the cheek-strap. Fig. 5 is a perspective rear view of the trimming.

25 Like letters of reference refer to like parts in the several figures.

A A represent the cheek-straps; B, an upward extension of one of the cheek-straps forming the crown-strap; C, the chin-strap; D, the throat-latch, and E the billet of the throat-latch.

I represents the trimmings or fastenings whereby the lower ends of the cheek-straps A are secured to the chin-strap C, and whereby

these straps are held in their proper relative position; and I' is a similar fastening, whereby one end of the throat-latch is rigidly secured to one of the cheek-straps A. Each of these trimmings is composed of a plate, i, which 40 rests against the outer side of one of the straps to be secured together, and is provided with an opening for a rivet, i', and hooks or claws, j, which extend rearwardly from both ends of one edge of the plate i in the angles formed 45 by the junction of the straps. In the trimmings I the claws j bear against the edges of the cheek-straps and overlap the top edge of the chin-strap, and in the trimming I' the claws bear against the edges of the throat-latch 50 and against the rear edge of the cheek-strap. The claws j serve to retain the straps in their proper relative position, and the rivets or lugs i' secure the trimmings to the strap and the straps to each other, the whole forming a very 55 simple and neat fastening.

If desired, a lug or rivet may be cast directly on the plates i, instead of providing said plates with an opening and inserting a rivet in the same, as hereinbefore described.

I claim as my invention—

A halter-trimming composed of a plate, i, and rearwardly-extending hooks or claws j, substantially as set forth.

Witness my hand this 23d day of July, 1883. 65

EDWARD A. COOPER.
